United States Patent Office.

ALBERT A. MURFEY, OF MONTVILLE, ASSIGNOR TO HIMSELF AND
NATHAN D. MORGAN, OF NORWICH, CONNECTICUT.

Letters Patent No. 94,632, dated September 7, 1869.

IMPROVEMENT IN PICTURE-FRAME.

The Schedule referred to in these Letters Patent and making part of the same.

To all persons to whom these presents may come:

Be it known that I, ALBERT A. MURFEY, of Montville, in the county of New London, and State of Connecticut, have invented a new and useful Picture-Frame; and do hereby declare the same to be fully described in the following specification, and represented in the accompanying drawings, of which—

Figure 1 is a front elevation,

Figure 2, a rear view, and

Figure 3, an edge view of one of the said frames.

Figure 4 is a transverse section of it.

In carrying out my invention, I take a sheet, A, of pasteboard or other suitable material, stellated in form, and I make through it a slot, *a*, and arrange against the ends of such slit, and so as to extend from the sheet two projections, or guides, *b b*, the same being as shown in Figure 5, which is a rear side view of such star of pasteboard, the slit being shown at *a*, and the guides at *b b*.

Next, I apply to the said sheet of pasteboard a pane or sheet of glass, *d*, and a mat or picture-border, *e*.

Next, should each of the star-points have its edges of greater width than it may be desirable to cover with thread, in manner as hereinafter described, I cover or cement about the parts of the edges to be left uncovered by the thread, cloth or other material of the color of the thread, such being as shown at *s*, in figs. 4 and 5.

Next, I wind on the star-points thread, commencing the wind at the edge of one point, and winding around it and the next parallel edge of a point a series of six or other suitable number of coils, laid close together.

Next, I turn the star ninety degrees, and make another series of winds at right angles with the first; and so I continue on until the whole points are covered, and a polygonal border is formed about a polygonal space and the glass plate.

The winding of the thread I sometimes perform in one direction and next in another, that is, I make a series of the winds, or coils, by winding on the star in one direction, and next I reverse the winding, or carry it in the opposite direction, the whole being productive of the effect as represented at *f* in the drawings.

The guides *b b* are to serve as bridges to keep the threads on the back of the picture-frame from covering the slit *a*, through which a photograph or picture is to be introduced into the space between the pasteboard and the pane of glass. Were it not for the guides, or bridges *b b*, to bend the threads about, the slit *a* would be liable to be covered by the thread.

Threads of different colors may be wound on the star, and so as to produce a very pleasing effect.

I claim the combination of the star with thread wound on its points, so as to form a polygonal opening, with a polygonal and star-pointed border encompassing such opening, as set forth, the said opening being for the reception of a picture.

Also, the combination of a pane of glass, or the same and a picture-mat, with the star and thread wound and arranged thereon, substantially as described.

Also, the combination of the thread-guides, or bridges *b b* with the opening, or mouth *a* of the star A, or with it and thread wound on such star, and against the said guides, in manner and for the purpose of making a border on the star, as set forth.

Also, the combination of the edge-coverings *s* with the star and the thread wound thereon, as set forth.

ALBERT A. MURFEY.
